UNITED STATES PATENT OFFICE

EBEN C. IVES, OF ST. PAUL, MINNESOTA

CHIME MECHANISM

Application filed October 19, 1928. Serial No. 313,497.

The present invention relates to scales and mechanism, which may be used with the more particularly to a coin actuated chime present invention.

In coin controlled weighing machine it is 5 desirable to have some novelty feature which will call the attention of the public to the presence of the machine, in addition to the attractive appearance of said machine.

An object of the present invention is to 10 make a sound device which will be actuated upon the completion of a weighing operation.

In order to attain this object there is provided in accordance with one feature of the 15 invention a releasable coin stop which will hold a coin suspended until after a weighing operation is completed, and upon completion of the weighing operation will release the coin permitting it to drop into a zigzag 20 run-way being provided with chimes at intervals therein positioned to be struck by the coin in its travel through said run-way to emit a musical chime effect thereby. These and other features of the invention 25 will be more fully brought out in the following description and the accompanying drawings, wherein:

Figure 1 is a view in perspective of the 30 front of the scale with a door of the chime compartment open and a portion of the coin receptacle broken away, to see the construction thereof.

Figure 2 is a view in vertical section 35 through the scale showing the arrangement of the various parts thereof.

Figure 3 is a view in rear elevation of the chime mechanism.

Figure 4 is a sectional view on the line 40 4-4 of Figure 3.

Figure 5 is a sectional view on the line 5-5 of Figure 3.

Figure 6 is a sectional view on the line 6-6 of Figure 3.

Figure 7 is a sectional view on the line 45 7-7 of Figure 3.

Figure 8 is a sectional view on the line 8-8 of Figure 3.

Figure 9 is a view in rear elevation of a 50 well known type of coin released weighing

mechanism which may be used with the present invention.

Figure 10 is a view in side elevation of a 55 coin stop which is controlled by the weighing mechanism.

Figure 11 is a view in perspective of a 60 coin stop release arm which is mounted on a plunger of the weighing mechanism.

Figure 12 is a view in perspective of a 65 coin stop pawl; and

Figure 13 is a view in perspective of the 70 coin stop pawl mounting member.

Referring to the drawings in detail a scale A is of a well known type having a plunger 1 which is connected to a suitable scale 65 mechanism of a well known type and to the weighing platform 2. This plunger is depressed by the weight of a person or object upon the weighing platform and travels downwardly. The weight registering mechanism comprises an arrow 3 and associated parts which are released for operation by the insertion of a coin in a coin slot 4. The plunger 1 is provided with an offset arm 5 which is positioned to engage a coin release pawl 6 on an upward movement of 75 said plunger.

The pawl 6 is pivotally mounted on a support member 7 the offset end portion 8 of 80 said pawl being positioned to enter a notch 9 and to be positioned transversely of a coin 85 slide 10 secured to the rear face of said support member 7. A coil spring 11 is connected to the support member 7 and to the pawl 6 to normally hold the pawl inwardly so that the offset end portion 8 thereof is positioned transversely of the coin slide 10 to 90 arrest the travel of a coin down said slide. The coin is inserted in the opening 4 provided therefor and drops into a receptacle 12 mounted on the upper end of the coin slide 10. As the coin drops into the receptacle 12 it trips a lever 13 which releases the scale plunger 1 for downward travel. The plunger 1 actuates the indicating arrow 3 95 in a well known manner to register the weight of the person or object upon the weighing platform.

Passing downwardly through the receptacle 12 the coin enters the coin slide 10 and 140

passes downwardly therethrough until it is arrested by the pawl 6 which is drawn inwardly by the spring 11 to lie transversely of the coin slide 10 when the plunger 1 is in a depressed condition. The coin is retained in position in the coin slide by the pawl 6 until the person or object is removed from the weighing platform 2 whereupon the plunger 1 is drawn upwardly by springs 14 and 15. The arm 5 connected to the plunger 1 strike the lower end 16 of the pawl 6 in its upward travel, moving the upward end of the pawl outwardly to release the coin. The coin upon being released, drops into a second receptacle 17 and from this receptacle the coin passes downwardly into a zigzag coin track 18. The zigzag coin slot 18 comprises vertical portions 19 and sloping transverse portions 20. A chime or bell 21 is mounted at the lower end of each vertical portion 19 of the zigzag coin track to be struck by the coin in its passage downwardly therethrough. The coin drops down the vertical portion 18 striking the chime 21 which is mounted on the lower end thereof, the coin then rolls down the sloping portion 20 to the second vertical portion where it strikes the second chime. This process is continued till all of the chimes have been struck and the coin rolls downwardly through the last sloping portion 20 from where it drops into a coin receptacle 22.

The chimes 21 are mounted upon brackets 23 which are supported upon the zigzag coin track 18. In the present construction the coin track 18 is cast in a single piece with a plate 24 of similar shape secured to the forward face thereof as by means of screws 25, see Figure 1.

By providing chimes of different tone a musical effect can be obtained which will attract attention to the presence of the scale and provide a novel and entertaining incentive to be of use thereof.

I claim:

1. In combination with a coin controlled mechanism, zigzag guide means positioned to receive a coin after actuating said coin controlled mechanism, said track having vertical and downwardly sloping portions, a sound emitting device positioned at the lower end of each vertical portion of said track to be struck by a coin dropping downwardly through said vertical portion of said track.

2. In combination with a coin controlled scale having a portion thereof adapted to move downwardly during a weighing operation, means positioned to receive a coin after releasing said scale mechanism for operative movement, means positioned to arrest the travel of a coin downwardly through said receiving means, means carried by said scale mechanism to engage said arresting

means upon a return of said scale mechanism to normal to release said coin arrested thereby, and a zigzag track positioned to receive a coin when released by said arresting mechanism, and sound emitting devices positioned at intervals on said zigzag track to be struck by said coin in its travel along said track.

3. In a sound emitting mechanism of the class described, comprising an inclined track positioned to receive a round object and rollingly transmit the same, said track having a plurality of reverse turns therein, releasable stop means positioned to arrest the travel of said object at a predetermined point, means for releasing said stop means, and a sound emitting device positioned at predetermined reverse turns in said track to be struck by said round object in rolling along the track.

4. In a sound emitting mechanism comprising a releasable stop means positioned to arrest the travel of a discoid member, means for releasing said stop means, a downwardly sloping track having its upper end positioned adjacent said stop means to receive said discoid object when released from said stop means, said track having a plurality of reverse turns therein and having an opening at each reverse turn thereof, and a vibratory sound emitting member positioned in each of said openings to be struck by said discoid object in rolling along said track, to produce a musical, vibratory tone and to deflect said discoid object in its path along the next succeeding track portion.

In testimony whereof I affix my signature.
EBEN C. IVES.
